UNITED STATES PATENT OFFICE.

JOHN W. WESTON, OF MOLUS, KENTUCKY.

LEVEL AND SQUARE.

1,319,545.

Specification of Letters Patent. Patented Oct. 21, 1919.

Application filed January 10, 1919. Serial No. 270,490.

To all whom it may concern:

Be it known that I, JOHN W. WESTON, a citizen of the United States, residing at Molus, in the county of Harlan and State 5 of Kentucky, have invented certain new and useful Improvements in Levels and Squares; and I do hereby declare the following to be a full, clear, and exact description of the invention, such as will enable others 10 skilled in the art to which it appertains to make and use the same.

This invention relates to levels and squares, and more particularly to an instrument of the character stated which is 15 especially adapted for use in connection with masonry work.

One of the main objects of the invention is to provide an instrument by means of 20 which a mason can readily ascertain if his work is square and level, the instrument being also adapted to be used for plumbing the work.

A further object is to provide a level and square in conjunction with a straight edge 25 especially adapted to be used therewith, this straight edge being provided with a frame by means of which a trowel and jointer may be supported so as to be readily accessible for truing up the work.

30 Another object is to provide simple and efficient means for securing the levels vials in operative position in the arms of the instrument.

Another object is to provide simple and 35 efficient means for detachably securing the arms of the instrument together at right angles to each other, so as to permit these arms to be readily disassembled, when desired, each arm constituting, when separated 40 from the other arm, a level.

Further objects will appear from the detailed description.

In the drawings:—

Figure 1 is a front view of a level and square constructed in accordance with my 45 invention, with the straight edge attachment applied.

Fig. 2 is an end view of the same,

Fig. 3 is a section taken substantially on 50 line 3—3 of Fig. 1,

Fig. 4 is a section taken substantially on line 4—4 of Fig. 1,

Fig. 5 is a section taken on line 5—5 of Fig. 1,

55 Fig. 6 is a section taken on line 6—6 of Fig. 5,

Fig. 7 is a detail perspective of one of the vial holders.

Fig. 8 is a section taken substantially on 60 line 9—9 of Fig. 8.

Fig. 9 is a section taken substantially on line 10—10 of Fig. 8.

In carrying my invention into effect I provide two arms 1 and 2, which are, preferably, though not necessarily, brass bound and graduated at their inner edges as illustrated. The inner end portion of arm 1 is cut away or reduced in thickness to provide a tongue 3 which fits snugly between coöperating flanges 4 formed at the inner end 70 of arm 2 by cutting this arm away to receive the tongue, the tongue and flanges coöperating in the well known manner to provide a tenon joint, by means of which the two arms may be connected at right angles to 75 each other. Arm 2 is provided with a recess 5 in its outer edge portion which receives an eye 6 formed at the lower end of one arm 7 of a securing member 8.

Arm 7 is of such length as to have its 80 upper end flush with the upper end of arm 2 of the square as illustrated. An arm 9 is hingedly secured as at 10, to the upper end of arm 7 and extends at right angles thereto longitudinally of arm 1 of the square so 85 as to fit snugly against the outer edge thereof. This arm 9 of member 8 has its free end portion turned down and shaped to provide a catch element 11 adapted to engage a shoulder 12 formed on the inner face 90 of a socket member 13 set into the upper edge of arm 1. The member 7 thus serves to secure the two arms of the square and level together and to maintain them at right angles to each other. This securing member 95 is supplemented by a releasable catch composed of a resilient hook member 14 which is pivotally secured at one end as at 15 to one side of arm 1, this hook member being provided with a hook 16 at its other 100 end which engages about a securing pin 17 carried by arm 2. The hook 14 serves to effectually prevent spreading apart of the arms, while the hinged securing member 7 effectually prevents movement of the arms 105 toward each other, the hook and securing member thus coöperating to effectually prevent any looseness or play between the arms of the instrument while insuring that these arms are held securely and accurately in 110 proper relation. By disengaging hook 14 from pin 17, and releasing element 9 of the

securing member 7 from socket member 13, the arms 1 and 2 may be readily separated so as to permit the instrument to be packed into a tool kit in such a manner as to occupy a minimum amount of space, each of these arms also constituting, when separated, a separate instrument which may be used as a level. Arm 1 is provided, at its central portion with an opening 18 extending through the arm, this opening receiving the supporting plates of vial holders indicated generally by 19. These vial holders serve to removably support two leveling vials 20 of suitable construction, these vials being mounted in parallel spaced relation and extending longitudinally of the arm 1. Adjacent each end this arm is provided with an opening 21 in which is supported a transversely extending leveling vial 22 by means of holders 23, which are of substantially the same construction as the holders 19. As will be noted more clearly from Figs. 3 and 7 of the drawings, each of the vial holders comprises a supporting plate 24 of substantial rectangular outline which is of such shape as to fit snugly within the opening 20 against the end wall thereof, this plate being provided at its upper and lower edges with outwardly projecting ears 25 to which are hinged the securing arms 26, the outer ends of which are shaped to provide resilient catch elements 27 adapted to engage about securing shoulders or heads 28 formed on the inner faces of socket members 29 set into the opposite faces of arm 1. The securing arms 26 coöperate with the socket members to efficiently secure the holders to the arms, the supporting plates 24 of these holders being positioned at opposite ends of the openings 20. A retaining plate 30 is secured to plate 24 in advance thereof and a pad 31, of felt, leather, or other suitable material is mounted between the two plates. The plate 30 is provided with spaced openings 32 which are adapted to receive snugly the end portions of the level vials 20, the ends of these vials fitting tightly against the pads 31 so as to be supported and held thereby. These pads act to tightly grip the ends of the vials so as to secure the same in proper position, while providing shock absorbing means which serve to prevent breakage of the vials from jars incident to use of the instrument.

The construction of the vial holders 23 is similar to that of holders 19 with the exception that the arms 26^a are bent into substantial rectangular or L-shape, so as to fit about the edge portion of arm 1, the catch element 27^a engaging over head 28^a formed at the opposite sides of a socket member 29^a which is set into the edge of arm 1. By means of these holders, the vials 20 and 22 may be readily secured on the arm 1 in proper operative position for use and may be quickly and easily removed, when not in use, so as

to reduce the danger of breakage thereof. Arm 2 is provided with a similar set of vials 20^a which are mounted in the same manner as the vials of arm 1 and disposed in the same relation. The two arms, each provided with the two sets of vials in the manner described, when secured together at right angles to each other as illustrated, constitute an instrument, by means of which it may be readily ascertained if any particular work is level and true. This instrument may also be used as a square in the usual manner, as will be understood. The instrument is also well adapted for use in placing window frames in buildings, as, by placing one of the arms upon the lower member of the frame, and the other arm in engagement with the side member or board of the frame, the user can ascertain at a glance if his frame is set so as to be level and plumb. In the same manner, the instrument can be used for determining if a piece of masonry is level and plumb or if a wall is at right angles to a given wall. In this manner this instrument saves considerable time and work to masons, carpenters and persons engaged in similar trades. This instrument is especially adapted for use in connection with a straight edge designated generally by 33. This straight edge includes a straight edge strip 34 from which is suspended the frame 35 formed from sheet metal by stamping and bending, this frame being provided adjacent each end with a supporting arm 36 which is bent about and secured to the straight edge strip 34. The upper end of arm 36 is connected by a chain 37 to a ring 38 slideable in a slot 39 extending longitudinally of a supporting member 40 projecting outwardly from arm 1 at right angles thereto. The member 40 is provided on its inner end with a T-head 41 which fits snugly into a channel member 42 set into arm 1 and fixedly secured therein. The upper end of member 42 is open so as to permit free insertion of head 41 into the same, the lower end of this member being closed as in Fig. 6 to positively limit the downward movement of the head. In this manner the straight edge strip 34 and the frame 35 are suspended from the upper arm 1 of the instrument so as to be adjustable toward and away from the frame. Arm 2 is also provided with channel members 42^a set therein corresponding to the channel members 42 by means of which the supporting members 40 can be mounted on this arm when arm 2 is uppermost. This permits the straight edge to be supported from either arm of the instrument so as to be readily accessible for truing up the work.

The straight edge frame 35 is turned inwardly at its lower edge to provide an integral right angularly disposed flange 35^a and the material of this flange at the lower

edge thereof is slit and offset to provide a depending supporting strip 35^b extending longitudinally of the frame 35. This strip slidably receives the end links of chains 43 and 44 provided at their lower ends with hooks 43^a and 44^a, respectively. Hook 43^a is adapted to engage through an eye 45 secured in the upper end of the handle of a pointer trowel 46, hook 44^a, engaging through a ring 47 secured to the upper end of a jointer 48. The trowel and the jointer are thus suspended from the straight edge frame so as to be readily accessible for jointing and truing up the work, thus effecting a material saving in time, as will be appreciated.

10 Arm 1 of the instrument is provided in its outer end with an eye 49 secured therein, a similar eye 50 being provided in the outer 20 end of arm 2. These eyes are adapted to receive a line for plumbing or for truing up the work in the well known manner.

It will be evident that there may be slight 25 changes made in the construction and arrangement of the details of my invention without departing from the field and scope of the same, and I intend to include all such variations, as fall within the scope of the appended claims, in this application in 30 which a preferred form only of my invention is disclosed.

What I claim is:—

1. In an instrument of the character described, a level arm provided with an opening, vial holding members detachably secured to said arm and extending through said opening at opposite sides thereof, and a level vial detachably mounted in said supporting members.

2. In vial supporting means for levels and similar instruments, the combination with a level arm provided with an opening, of socket members carried by said arm, supporting plates, a holding plate carried by each of said supporting plates provided with an opening for receiving the end portion of a level vial, and securing arms hingedly secured to the opposite edges of said sup-

porting plates and engaging into said socket members so as to detachably secure the supporting plates within said openings.

3. A vial holder adapted for use in connection with levels and similar instruments, comprising a level arm provided with an opening therethrough, a base plate, securing arms hingedly secured thereto at the opposite edges of said plate and adapted to engage about the opposite faces of said level arm when the base plate is mounted within the opening provided through said arm, each of said securing arms provided at its free end with a catch element adapted to coöperate with a catch element provided on the level arm for detachably securing the holder in position, and means carried by the plate for receiving the end portion of a level vial so as to detachably hold the vial in operative position.

4. In an instrument of the character described, two arms detachably connected together at their adjacent ends by a tenon joint, said arms disposed substantially at right angles to each other, a catch element carried by one of said arms at the outer edge thereof, a securing member pivotally secured at one end to the other arm, said member comprising two elements hingedly secured together and of such length as to fit snugly about the outer edge portions of the adjacent ends of the arms at right angles to each other, the outer one of said elements being provided at its free end with a catch element adapted to coöperate with the catch element carried by the other arm so as to detachably secure said securing member in operative position, the securing member acting to prevent movement of the arms of the instrument toward each other, and detachable means for preventing movement of said arms away from each other.

In testimony whereof I affix my signature in presence of two witnesses.

JOHN W. WESTON.
